UNITED STATES PATENT OFFICE.

ARTHUR E. SMALL, OF CHICAGO, ILLINOIS, ASSIGNOR TO UNION METAL PRODUCTS COMPANY, OF CHICAGO, ILLINOIS, A CORPORATION OF DELAWARE.

POSITIONING DEVICE FOR RAILWAY-CAR COUPLERS.

Application filed June 16, 1926. Serial No. 116,407.

This device relates to means for automatically positioning the coupler of a railway car by gravity.

Two railway cars are automatically coupled together by the movement of their respective couplers forcing the tails of the pivoted knuckles behind gravity locks. The couplers are mounted in the cars so as to permit a limited amount of lateral movement. Such limitation is necessary and essential because if the couplers were allowed to move too far to either side, the couplers of the two cars being coupled would pass each other and not couple, thereby defeating the object of the automatic coupler. The greater the lateral movement of a coupler the less side pressure on the striking casting when the cars are going around curves. This lateral pressure forces the wheel flanges 20 against the rail causing considerable friction and wearing of the rails and wheels.

One of the objects of the invention is to increase the amount of permissible lateral movement of a coupler by providing automatic means for returning the couplers to the longitudinal center of the car or at least close enough thereto so that the automatic couplers will couple. This is what is termed the "coupling range."

It is very often necessary to couple cars on curves and frequently when the radius of the curve is very small, as is common around industrial plants, the couplers of the two cars will be so far out of alignment that they will not automatically couple. Another object of the invention is to automatically bring such couplers within coupling range. The outside rail of a curved track is raised above the inside rail and I provide means whereby the coupler is moved toward the inside of the curve by gravity. This automatic gravity means also returns the coupler to the longitudinal center of the car when the car moves from the curved to the straight part of the track.

In my device the lateral movement between the coupler and the carrier is eliminated, thus reducing friction and consequent wear on the parts. This is quite an item particularly in sandy countries because couplers are costly and the replacement of a coupler means keeping the car out of service.

Coupler positioning devices reduces the number of broken knuckles and guard arms on couplers which members are frequently 55 bent or broken when the couplers are not within coupling range. Such devices also reduce the number of accidents to trainmen as they are not required to go between the cars and position the coupler preparatory to 60 coupling.

A common form of car coupler positioning device comprises a coupler carrier swingably suspended by links from some part of the car so that the objects and advantages 65 mentioned above are obtained and my invention is an improvement upon such devices and consists in providing a shiftable bearing construction to increase the eccentricity of the weight of the coupler (and its associated 70 parts) about its point of support, thus increasing the resultant force tending to return the coupler to the longitudinal center of the car (or away therefrom when the car is tipped). 75

In my device the coupler carrier is swingably suspended from any convenient part of the car by a link at each of its ends and is provided with means, such as lugs, to prevent lateral movement of the coupler relative thereto. These links have a rolling engagement with the supporting car part and the carrier. The engaging surfaces are non-concentric with each other so that upon lateral swing of the link, one of said surfaces 80 rolls upon the other surface and gradually shifts the contacting or engaging line therebetween. The curved surfaces may be ar- 85 cuate or of any desired contour.

In the drawings:

Fig. 1 shows a typical application of the device to a railway car.

Fig. 2 is a section on line 2-2 of Fig. 1.

Fig. 3 is a side elevation of Fig. 1.

Figs. 4 and 5 are skeleton diagrams showing the device respectively in normal position and with the carrier moved laterally.

Fig. 6 is a perspective view of a link.

Figs. 1, 2 and 3 show a typical application of the device to a car wherein the coupler carrier element 3 is swingably suspended at its opposite ends to the striking casting (or other car part 5) by the links 2. The car part element 5 is provided with rela- 100

tively flat upper bearing surfaces 30 and the carrier 3 is provided with a relatively flat lower bearing surface 31. One (or preferably both) of the links has a curved bearing surface (32-33) at each end which engage the bearing surfaces (30-31) of the car part and carrier, respectively. The links may be provided with lateral extensions to increase the length of the curved bearing surface. Figs. 4 and 5 show this adaptation (with the immaterial parts of the car omitted) in normal and upon extreme lateral movement of the coupler 8.

In the usual centering device link, which is pivoted at both ends, the eccentricity of the load upon the link is equal to the lateral swing "A" of the carrier, but in my arrangement this eccentricity is increased by the distance the link rolls upon the car part. In other words, when the carrier moves distance "A" (Fig. 5) the eccentricity is distance "B", which is greater than "A".

As one surface rolls upon the other the effective radius of the link is changed and the parts may be so proportioned as to maintain the same radius, or to increase or decrease it, as desired. In any event the eccentricity of the load about its support is increased.

It is desirable to provide some means to prevent slippage between the engaging surfaces, thus forming one surface to roll upon the other, thereby maintaining operative relation between the parts of the device. This may be accomplished by a rack and tooth arrangement or by a single tooth 20 engaging a depression 21 in the other element or the link may be held in place resting between oppositely disposed portions 22-23 of the car part (or carrier).

The broad idea of shifting the bearings between the link and a car part and between the link and the carrier (either one or both) is covered by applications for patents, Serial No. 116,406, and No. 116,408, filed June 16, 1926, which applications also claim certain details of construction.

The accompanying drawings illustrate the preferred form of the invention, though it is to be understood that the invention is not limited to the exact details of construction shown and described, as it is obvious that various modifications thereof within the scope of the claims will occur to persons skilled in the art.

I claim:

1. In a railway car; the combination of a car part element, a coupler carrier element, and a pair of links swingably suspending the opposite ends of the carrier thereto, non-concentric engaging surfaces between one of said links and one of said elements whereby upon lateral swing of the link, one of said surfaces rolls upon the other and gradually shifts the contacting line therebetween, one of said surfaces having a projection which

operatively engages a depression in the other of said surfaces constituting means to maintain operative relation between the elements.

2. In a railway car; the combination of a car part element, a coupler carrier element, and a pair of links swingably suspending the opposite ends of the carrier thereto, upwardly projecting eccentric rolling engaging surfaces between one of said links and one of said elements, whereby upon lateral swing of the link the place of contact between the link and its adjacent element is shifted.

3. In a railway car; the combination of a car part element, a coupler carrier element, and a pair of links swingably suspending the opposite ends of the carrier thereto, one of said links provided with lateral extensions, upwardly projecting eccentric rolling engaging surfaces between said extensions and one of said elements, whereby upon lateral swing of the link the place of contact between the link and its adjacent element is shifted.

4. In a railway car; the combination of a car part element, a coupler carrier element, and a pair of links swingably suspending the opposite ends of the carrier thereto, said links having curved bearing surfaces projecting toward and engaging flat bearing surfaces on the car part and carrier respectively, whereby upon lateral swing of the link the line of contact between the link and the element is shifted.

5. In a railway car; the combination of a car part element, a coupler carrier element, and a pair of links swingably suspending the opposite ends of the carrier thereto, said links provided with lateral extensions having curved bearing surfaces projecting toward and engaging flat bearing surfaces on the car part and carrier respectively, whereby upon lateral swing of the link the line of contact between the link and the element is shifted.

6. In a railway car; the combination of a car part element, a coupler carrier element, and a pair of links swingably suspending the opposite ends of the carrier thereto, said links having curved bearing surfaces projecting toward and engaging flat bearing surfaces on the car part and carrier respectively, whereby upon lateral swing of the link the line of contact between the link and the element is shifted, each curved bearing surface having a projection which operatively engages a depression in the flat bearing surface constituting means to maintain operative relation between the elements.

7. In a railway car; the combination of a car part having a slot with upwardly projecting bearing surfaces on opposite sides thereof, a coupler carrier and a pair of links swingably suspending said carrier from said car part, one of said links having oppositely projecting trunnions at one end thereof, each

trunnion having a downwardly projecting rolling surface eccentric from and engaging said bearing surfaces.

8. In a railway car; the combination of a car part having a slot with straight bearing surfaces on opposite sides thereof, a coupler carrier and a pair of links swingably

suspending said carrier from said car part, one of said links having oppositely projecting trunnions at one end thereof, each trunnion having a downwardly projecting rolling surface engaging said bearing surfaces. ¹⁰
